UNITED STATES PATENT OFFICE.

ARCHIBALD W. PAULL, OF WHEELING, WEST VIRGINIA.

IMPROVEMENT IN PROCESSES OF PREPARING WALL-PAPER.

Specification forming part of Letters Patent No. **140,533**, dated July 1, 1873; application filed January 23, 1873.

To all whom it may concern:

Be it known that I, ARCHIBALD W. PAULL, of Wheeling, in the county of Ohio and State of West Virginia, have invented a new Process of Preparing Wall-Papers, of which the following is a specification:

The invention will first be fully described in connection with all that is necessary to a full understanding thereof, and then clearly pointed out in the claim.

Wall-papers have heretofore been prepared by making the design or figures upon a die plate or block, and then imprinting that upon the paper. I simply have a carefully-selected and artistic design, prepared on paper, wood, or other material, and photograph it directly upon the wall-paper. In this manner I am able to secure as many fac-similes as I wish of

a design whose delicacy of tint, exact imitation of nature, and elaborate ornamentation are absolutely impossible in the block-printing process. Again, by my process a single copy of a design may be enlarged or diminished in size to suit different heights of ceilings, thus securing an exactitude of correspondence between the paper and apartment which is unattainable in wall-paper at the present time.

Having thus described my invention, what I claim as new, and desire to secure by Letters Patent, is—

The process of preparing wall-papers, substantially as above described.

ARCHIBALD W. PAULL.
